FIG. 4.

FIG. 5.

FIG. 6.

INVENTOR:

William C. Chick

By *Frank D. Hayes*

ATTORNEYS.

UNITED STATES PATENT OFFICE.

WILLIAM C. CHICK, OF BOSTON, MASSACHUSETTS.

SHAKER.

Application filed October 19, 1922. Serial No. 595,664.

To all whom it may concern:

Be it known that I, WILLIAM C. CHICK, of Boston, in the county of Suffolk and State of Massachusetts, a citizen of the 5 United States, have invented a new and useful Improvement in Shakers, of which the following is a specification.

A shaker, that is a vessel in which various liquids are to be mixed together and perhaps chilled with cracked ice, is usually made of very thin metal and hence is liable to be bent more or less out of shape in transportation so that its cover will not fit tightly and during the shaking process the liquid 10 will leak out. Drinking cups have also been made of thin metal, but in rings so that they may be collapsed and packed in small compass. Shakers have not hitherto been made in collapsible form for the reason presumably that during the handling to which they 15 are submitted while in use there is danger that they will accidentally collapse and spill the liquid.

My invention is intended primarily to 20 provide a vessel of this general character with means to prevent its being collapsed while in use, which means will also serve to lock the vessel when in collapsed form so that it will not open out during transportation. It will be understood by reference to 25 the drawings in which it is shown applied to a shaker and in its preferred form.

Figure 1 is an elevation showing the vessel in its open or usable form;

Fig. 2 being a vertical section on line 2—2 of Fig. 1.

Fig. 3 is a plan.

Fig. 4 shows the same vessel in collapsed position;

Fig. 5 being a section on the line 5—5 of Fig. 4, and

Fig. 6 being a plan of the collapsed vessel.

The vessel as shown comprises three sections 1, 2, 3, and a cover. The cover as 45 shown comprises a ring 5 and above it a conical portion 6 which terminates in a neck 7 closed by a removable cap 8. The diameter of the neck 7 is somewhat smaller than the ring 5 so as to provide an easy means 50 of emptying the vessel. The cap 8 has preferably in its centre a pin 9. The section 1 is closed at the bottom and each section 1, 2 and 3 is slightly smaller than the one next 55 above it, all of them being conical in character and of thin metal, and sections 2 and 3 being open at both ends, so that the lower

edge of section 2 encloses and makes a tight sliding fit with the top of section 1; so also with sections 2 and 3, this construction being well known in the collapsible cup art. 60

The bottom of section 1 is flanged as at 10 and to the flange is hinged at 4 preferably a plurality of braces. These braces are in two parts 11 and 12 hinged together at 13, the part 12 having a stop 14 cut and bent 65 from it so that when the shaker is in usable condition as shown in Figs. 1 and 2 these stops will engage the outside of one of the sections, for example the section 2 as shown, and limit the inward throw of the brace. 70 The lower part 11 is longer than the upper part and both are made of metal and act much as toggles. The section 3 has a perforated lug 15 attached to it near its top and the upper part 12 of each brace has a narrow 75 tongue 16 which will fit into the perforation 17 in the lug. Preferably the location of the lug 15 and the relative lengths of the parts 11 and 12 are such that when the tongue 16 of each brace fits into the perforation in its lug 15 the parts 12 and 11 will lie at a slight concave angle to each other, so slight that it cannot be indicated in the drawings but sufficient to spring the braces as a whole past their dead centre toward 80 the axis of the shaker and so lock themselves in position to give a firm support to the shaker as a whole, the longer parts 11 springing slightly for this purpose.

It will thus be seen that owing to the 85 flange 10 the shaker has a broad foundation on which it may rest on a table for example, and owing to the braces its parts are held firmly in extended position so that the vessel cannot collapse. The cover 5 which sets 90 into the top of section 3 and its cap 8 may be held in the hands of the user and the shaker used in the ordinary way without 95 danger of collapsing.

A strainer 18 is preferably placed on top 100 of the cover but below its neck to prevent the ice, etc. from being poured out after the shaking operation has taken place.

When it is desired to close this shaker for packing, the part 12 of the brace is unlocked 105 from the perforations 16 in lugs 15 and the vessel is then collapsed into the position shown in Fig. 5. Each part 12 has a perforation 20 in it sufficiently large to fit over the pin 9, and the length of the section 11 of 110 each brace is sufficient to bring its hinge 13 substantially on a level with the top of the

cap 8 when the vessel is collapsed. Thus the parts 12 of the brace may be folded over horizontally as shown in Fig. 5 and the perforations 20 slipped over the pin 9 so that the top view of the device as a whole is as shown in Fig. 6. Thus the pin 9 and the perforations 20 serve together to fasten the vessel in collapsed position. I have found this to be a simple means of so doing, but other means may be used if desired. The section 3 may be turned slightly when collapsed to bring the lugs 15 out of register with the part 11 of the braces.

It is believed that the advantage of this construction will be evident as it results in a device convenient for packing and protected not only by the cover and the flange 10 at the two ends but also by the parts 11 which serve to some extent to keep other articles from touching it in a closely packed lunch basket for example.

By my invention the shaker may be made of any desired number of sections and have any desired number of braces and may be collapsed in such a manner that it can be enclosed in a comparatively small box if desired. I have found three braces arranged an equal distance apart about the shaker to be sufficient for all ordinary uses, but the number may be varied depending upon the size of the device.

It is apparent that the principle of applying sectional braces to a sectional vessel in the manner above described may be otherwise embodied and that the shape of the cover may be changed without departing from my invention as stated in the claims, the particular feature of novelty being the use of braces in a sectional vessel which may serve to hold the vessel in extended position and if desired may also by engagement with the cover lock it when the vessel is in closed position. While the braces are shown hinged to the flange they may be otherwise connected therewith to perform their bracing function.

What I claim as my invention is:—

1. A vessel of the kind described comprising a series of sections of graduated size and a plurality of braces, one end of each brace being connected to a section at one end of the vessel and adapted to engage with a section at the other end of the vessel whereby said sections will be held in extended relation and upon the disengagement of said braces may be collapsed said braces being made in two parts whereby when said sections are in collapsed position said braces may be folded over the free end of the vessel and hold it in collapsed position.

2. A vessel of the kind described comprising

ing a series of sections of graduated size and a plurality of braces, one end of each brace being connected to a section at the end of the vessel and adapted to engage with a section at the other end of the vessel, whereby said sections will be held in extended relation and upon the disengagement of said braces may be collapsed, said braces being made in two parts permanently hinged together, in combination with a cover and means whereby when said vessel is in collapsed position said braces may be folded over said cover and their ends connected to keep said vessel from opening.

3. A vessel of the kind described comprising annular sections of graduated size adapted when extended to form a liquid-containing vessel and means to hold said sections in extended relation, said means comprising braces made in two parts permanently hinged together, one of said parts being hinged to one of the end sections and the other adapted to engage the other end section and prevent it from moving toward the first end section and when said sections are collapsed to fold over one of the end sections.

4. A vessel of the kind described comprising sections of graduated size adapted when extended to form a liquid-containing vessel and means to hold said sections in extended relation, said means comprising braces located to engage two end sections, said braces being slightly longer than the distance between the points at which they engage the two end sections when said sections are extended, whereby they will be sprung into bracing position, in combination with stops located to limit the inward movement of each brace when in bracing position.

5. A collapsible vessel having a cover, hinged braces adapted to hold said vessel in extended position and when said vessel is in collapsed position to be folded to meet over the cover of said vessel and hold it in said collapsed position.

6. A collapsible vessel of the kind described comprising a series of sections of graduated size, a plurality of sectional braces, one end of each brace being attached to one of the end sections of said vessel, the section at the other end of the vessel having means to engage the free end of each brace, said braces being slightly longer than the distance between these points of attachment to and engagement with the end sections of said vessel, whereby they will be sprung into position when said vessel is being opened, each brace having a stop to engage the side of said vessel and hold it in proper relation thereto.

WM. C. CHICK.
